UNITED STATES PATENT OFFICE.

FRANZ PRÁSIL, OF ZURICH, SWITZERLAND:

TURBINE.

SPECIFICATION forming part of Letters Patent No. 629,700, dated July 25, 1899.

Application filed September 24, 1898. Serial No. 691,798. (No model.)

To all whom it may concern:

Be it known that I, FRANZ PRÁSIL, a subject of the Emperor of Austria-Hungary, and a resident of Zurich, in the Republic of Switzerland, have invented new and useful Improvements in Turbines, (for which I applied for a patent in Switzerland on the 10th of March, 1898, and in Germany on the 19th of March, 1898,) of which the following is a specification.

My invention has relation to turbines; and it has for its object the provision of means whereby the velocity of flow under a given head or pressure of water is materially increased before acting upon the turbine driving-wheel, whereby the power exerted by the latter is correspondingly increased.

In the accompanying drawings, Figure 1 is a sectional elevation of a turbine embodying my invention. Fig. 2 is a plan view of one-half of the fixed directing-wheel. Fig. 3 is a like view showing part of the intermediate revoluble bucket-wheel and part of the driving-wheel. Fig. 4 is a fragmentary sectional view illustrating the construction and relative arrangement of the inner buckets of the non-revoluble or distributing wheel and the corresponding buckets of the intermediate revoluble wheel and of the driving-wheel; and Fig. 5 is a similar view illustrating the construction and relative arrangement of the outer buckets of the non-revoluble wheel and the like buckets of the intermediate revoluble wheel.

Referring to Fig. 1, H indicates the cylindrical housing which receives the water from an overhead supply, said housing being secured to a base-ring c, itself supported by suitable means at a proper elevation above the level U W of discharge, and to said base-ring is secured a distributing-wheel C, having two circular rows of buckets C' and C², the buckets C² of the inner circle of such having vertical directing-walls, while the buckets C' of the outer circle are constructed to discharge forwardly.

In a suitable step a' is stepped the driving-shaft a, which passes freely through a tubular shaft b, to the lower end of which is secured the intermediate bucket-wheel B, said shaft being supported above the upper water-level

O W in a cup formed in a sleeve b', which sleeve is revoluble in a suitable bearing b², said tubular shaft revolving freely in an axial bearing on the hub of the non-revoluble distributing-wheel C. The revoluble intermediate bucket-wheel B has also two concentric series of buckets B' and B², the inner buckets B² being constructed to discharge forwardly and receive the water from the inner circle of buckets C² of the distributing-wheel C. The outer buckets B' of the revoluble wheel B are constructed to discharge the water received from the outer buckets C' of the wheel C backwardly, Figs. 4 and 5.

To the shaft a below bucket-wheel B is secured the drive-wheel A, having but one circular series of buckets A', which receive the water from the inner buckets B² of the intermediate bucket-wheel B, said buckets A' discharging backwardly. The construction of the buckets of these wheels is well known, but their relative arrangement is such as to increase the velocity of flow under a given head or pressure before acting upon the driving-wheel. Both wheels A and B are impulse-wheels. The water from the forwardly-discharging outer buckets C' of the distributing-wheel C acts upon the backwardly-discharging outer buckets B' of the intermediate wheel B, while the water flowing straight down the inner buckets C² of said distributing-wheel C acts upon the corresponding forwardly-discharging buckets B² of the intermediate wheel, and these latter again discharge into the backwardly-discharging buckets A' of the drive-wheel A, whereby the speed of the flow of water acting upon the buckets A' of wheel A is materially increased, so that the drive-wheel will revolve at a greater speed under a given head or fall of water than would be the case otherwise.

Having thus described my invention, what I claim as new therein, and desire to secure by Letters Patent, is—

1. A turbine comprising a non-revoluble distributing-wheel having two concentric series of buckets, a driving-wheel having a single series of buckets, and an intermediate wheel having two concentric series of buckets and revolving independently of the driving-wheel, the buckets of said wheels constructed

to drive the intermediate and driving wheels in one and the same direction, substantially as and for the purpose set forth.

2. In a turbine, the combination of a non-revolvle bucket-wheel, a driving bucket-wheel, and an intermediate bucket-wheel revoluble independently of said driving-wheel, said intermediate wheel having buckets discharging forwardly into backwardly-discharging buckets of the driving-wheel, said non-revolvle wheel having buckets discharging vertically into the forwardly-discharging

buckets of the intermediate wheel, and said non-revolvle wheel having a second series of buckets discharging forwardly into a corresponding series of backwardly-discharging buckets of the intermediate wheel, for the purpose set forth. 15

In witness whereof I have hereunto set my hand in the presence of two witnesses.

FRANZ PRÁSIL.
